HENRY SELBY HELE-SHAW, OF LONDON, ENGLAND

COLLAR FOR PERSONAL WEAR

Application filed March 1, 1932, Serial No. 596,098, and in Great Britain December 8, 1931.

The present invention comprises a collar for personal wear of the double or turn-over kind which provides ease of movement and freedom of adjustment of the necktie between 5 the two bands of a stiff (as opposed to a soft) collar.

The double or turn-over collar for neck-wear presents a geometric problem of difficulty as not only must the necktie move freely 10 when the fold is made between the outer and inner bands and the collar bent round the neck but the edge of the fold must be smooth and even.

The invention will be described and explained with reference to the accompanying 15 drawings.

Fig. 1 shows a straight piece of material which has been folded over in the form of a collar.

20 Fig. 2 shows the effect of bending the article illustrated in Fig. 1 round the neck and with a necktie between the bands.

Fig. 3 shows a flat piece of more or less stiff material, such as starched linen, linen 25 covered paper, celluloid or other material used for making collars in which corrugations have been made extending inwards from one edge to the line *h*—*i* with the material in flat form.

30 Fig. 4 shows effect of folding the article of Fig. 3 along the line *f*—*g* and bending it round the neck.

Fig. 5 shows a piece of material which has been first bent along the turnover line and 35 then corrugated at one side of the line of bend.

Fig. 6 shows various forms of corrugation which may be employed,

40 *e* being an angular form of corrugation, *f* an ordinary circular arcuate corrugation, and

45 *g* a castellated form of corrugation, which is deepest at lower or outer edge of the inner band.

Fig. 7 shows a collar corrugated and bent round into the usual form, and

50 Fig. 8 shows a modified form of the corrugation in which small ridges or projections are formed on the corrugations at the outer edge of the band.

Referring to Figs. 1 and 2, a straight piece of material having two straight parallel sides is folded along its middle line in the form of a collar of which *a* is the inner band and *b* the outer band. When this collar is bent

round the neck it is deformed, bulges *c* being produced in the inner band and deformations *d* in the top edge. The deformation of the collar causes the tie *e* to be gripped so that considerable force would have to be employed to move the tie between the inner and outer bands. Fig. 3 shows a similar flat piece of material which may be folded along its middle line *f*—*g* to form a collar in which the part which will constitute the inner band has been provided with tapering corrugations (as shown at *j*) extending inwards from its edge to the line *h*—*i*. The corrugating has been effected while the material was flat. When the material is thereafter folded along the line *f*—*g* and the article is bent round in the form of a collar as shown in Fig. 4 bulges *c* still appear in the inner band but the edge of the fold is smooth. At the same time, however, an easy and smooth movement is provided for the tie due to the flexibility which has been imparted to the band by the corrugations *j*.

If now the piece of material is first bent along its middle line and the part which will constitute the outer band *b* is allowed to stand at a considerable angle, preferably a right angle, to the part which will constitute the inner band *a* while the corrugations *j* are formed in the inner band, then the lower edge *k* (Fig. 5) will become curved and when such a collar is bent round the neck as shown in Fig. 7 the bulges *c* of Figs. 2 and 4 no longer appear and a space may even be produced between the inner and outer bands. It is now found that the tie will move freely 90 between the inner and outer bands.

The corrugations may be of various shapes, certain forms being shown in Fig. 6. The corrugations are deepest at the lower edge of the inner band and they extend across approximately the whole width of said band; they are narrow and close together and blend into one another laterally.

I prefer to produce the corrugations by means of a pair of toothed rollers between which the band is passed. The apparatus and the method of producing the corrugations is described more particularly in the specification of my co-pending application No. 640, 308, filed October 29, 1932.

In the modification of the invention illustrated in Fig. 8 projections or ridges *l* are formed on certain of the inwardly-projecting parts of the corrugations on the inside

of the inner band near the lower edge *k*. These ridges or projections *l* assist in keeping the tie in position between the inner and outer bands.

5 The invention has been described as applied to a collar formed from a flat parallel edged piece of material but it will be understood that it can be applied to a collar formed from a shaped piece of material or to an existing collar when the benefits of the invention will accrue. The material of the collar may be linen, linen faced paper, paper, celluloid or other material.

10 The invention provides a flexibility in the inner band combined with increased rigidity in the vertical direction. This produces a collar which is comfortable to wear and prevents injury to the necktie or the stud holes of the collar. The necessity of forming a 15 linen collar of two pieces of different curvature at the turnover band is avoided. If stiff material for a collar is first bent over along the turnover edge and the inner band corrugated whilst the outer band is allowed 20 to take up its natural curve the length of a collar is not appreciably changed (the material not being stretched), although the overall length of the lower edge of the inner band is shortened.

25 30 It is found that after washing linen collars according to the invention the corrugations disappear and the collar when subsequently starched is not materially altered in length, so that it remains of the specified 35 standard size.

35 It will be observed that by reason of this invention a collar can be manufactured from a single piece of usual material; this material does not even need to be curved at the edge 40 that is to be the lower edge of the inner band, since the desired curve can be produced by the act of corrugating. This is of considerable 45 importance in the manufacture of so-called paper and other cheap collars as it provides the necessary spring.

What I claim is:—

50 1. A method of producing a stiff double collar with freedom for tie manipulation from a single piece of stiff plane material by bending the material along a turn-over line to form it into an inner and an outer band, and providing the collar with curvature by impressing, while the inner band is 55 at a considerable angle to the outer band, in the inner band and along approximately its whole length a large number of closely-disposed tapering corrugations of small width blending into one another laterally and extending transversely from the lower edge of 60 the band approximately to the line of the turnover so as to shorten the overall length of the lower edge of the band without, to any appreciable extent, altering the actual size of the collar or stretching the material 65 of the inner band.

2. A method of producing a stiff double collar with freedom for tie manipulation from a single piece of stiff plane material having its two long edges straight and parallel, which method comprises bending the material along a straight turnover line to form it into an inner and an outer band, and providing the collar with the whole curvature necessary by impressing, while the inner band is at a considerable angle to the outer band, in the inner band and along approximately its whole length a large number of closely-disposed tapering corrugations of small arc blending into one another laterally and extending transversely from the lower edge of the band approximately to the line of the turnover so as to shorten the overall length of the lower edge of the band without, to any appreciable extent, altering the actual size of the collar or stretching the material of the inner band.

70 75 80 85 90 95 3. A method of producing a double collar with freedom for tie manipulation which comprises impressing in the inner band of the collar and along substantially its whole length a large number of closely disposed corrugations extending transversely from the lower edge of the band substantially to the line of the turnover, while maintaining the outer band in a curved position.

100 4. A stiff collar comprising inner and outer bands, said inner band having a large number of closely disposed corrugations arranged along substantially its whole length and extending transversely from the lower edge of the band to points adjacent the juncture of the inner and outer bands, and ridges arranged on portions of the corrugations adjacent the lower edge of the band and adapted to engage the lower margin of a tie arranged in the collar.

105 5. A method of producing a stiff double collar with freedom for tie manipulation, which method comprises bending the material along a straight turn-over line to form it into an inner and an outer band, and providing the collar with the whole curvature necessary by impressing, while the inner band is at a considerable angle to the outer band and the outer band is curved with its inner face concave, in the inner band and along approximately its whole length a large number of closely-disposed tapering corrugations of small width blending into one another laterally and extending transversely through the lower edge of the band approximately to the line of the turnover so as to shorten the overall length of the lower edge of the said inner band without, to any appreciable extent, altering the actual size of the collar or stretching the material of the inner band.

110 115 120 125 130 Dated this 17th day of February, 1932.

HENRY SELBY HELE-SHAW.
